UNITED STATES PATENT OFFICE

JOHN P. NORTHEY AND RODNEY V. NORTHEY, OF TORONTO, ONTARIO, CANADA, AS
SIGNORS TO CONSOLIDATED BOLT COMPANY LIMITED, OF TORONTO, CANADA

KEY BOLT

Application filed February 3, 1928. Serial No. 251,590.

This invention relates to key bolts of the type disclosed in the United States Patent to Frederick L. H. Sims No. 1,266,334, dated May 14th, 1918, in which the key bolt is divided from the inner end of its slot to and through the head. As such bolts have heretofore been made, they fall short of the ideal in the following respects:

(a) As the bolt must be positioned in a rail joint with the slot inclined to the rail base so that the key may be driven without interference from adjoining bolts, the plane of the division between the halves of the bolt is not parallel to the rail base, and pressure of the rail longitudinally of the base therefore comes unevenly against the parts of the bolt and tends to distort the bolt by displacing the parts.

(b) To prevent the key backing out when the bolt is in use, it is desirable to have the key fit the slot tightly, so that it is frictionally gripped by its sides. As the bolt has heretofore been made, it has been essential to have the slotted portion a loose fit in the angle bar with which it is used so that it may be readily positioned. The parts in this case are too readily sprung apart to give as good a grip on the sides of the key as is desirable.

(c) As so far made, unless expensive specially forged blanks were employed, the length of the toe of the bolt could not be made sufficiently great to develop the full tensile strength of the shank of the bolt.

(d) As the bolt neck has so far been made, it has been difficult to give it the desirable tight fit in the angle bar without making it difficult to position the bolt in the angle bars and rail.

In the present invention it is our object to provide a bolt which will overcome the defects referred to.

The invention is hereinafter fully described and is illustrated in the accompanying drawings in which

Fig. 1 is a side elevation of my improved key bolt, looking in the direction of the arrow 1 in Fig. 3;

Fig. 2 a side elevation, looking in the direction of the arrow 2 in Fig. 3;

Fig. 3 a section on the line 3—3 in Fig. 1;

Fig. 4 a section on the line 4—4 in Fig. 1; and

Fig. 5 a side elevation of the blank from which the bolt is formed.

In the drawings like numerals of reference indicate corresponding parts in the different figures.

1 is a blank from which the bolt is to be formed. If the finished bolt is to be substantially cylindrical, the blank is formed of half-round bar steel. This half-round bar is bent over a mandrel having the form in cross section of the desired slot 4 in the bolt and the parts brought into parallelism. The parts at the slotted end of the bolt are then rolled or drawn down to reduce their cross sectional area, leaving the metal at its full cross sectional area where the end of the bolt is intersected by the median plane of the slot. Assuming the half-round blank to have a radius of the reduction of the parts between which the slot is formed is carried out until the extreme diameter, including the 17/64 of an inch slot, is 31/32 of an inch.

In the process of forming the bolt, however, the parts adjacent the slot are formed with a slight taper, the taper preferably beginning at the line a—a, which is approximately the position of the outer side of the adjacent angle bar of the rail joint in which the bolt is used. The taper is slight, but is sufficient to facilitate the passage of the end of the bolt through the hole in the angle bar. The bolt may thus be caused to have a tight fit in the angle bar when in position. This is of great value, as it is desirable to use a tight fitting key with the bolt so as to obtain full advantage of the frictional engagement of the side of the key with the sides of the slot to resist accidental backing out of the key.

The tight fitting of the key in the angle bar prevents the spreading of the halves of the bolt when the key is driven and maintains the frictional grip at a maximum.

The neck 2 of the bolt is of elliptical form close to the head, but, instead of terminating at the inner side of the neck in a more or less abrupt shoulder, it is tapered down substantially to the cylindrical form of the unslotted shank of the bolt. This facilitates the

entrance of the neck into the hole in the adjacent angle bar at or about the time the portion of the slotted end of the bolt of greatest diameter is becoming positioned in the opposite angle bar.

5 As hereinbefore stated, the slot in a direction transverse of the bolt must be inclined upwardly when the bolt is in position in a rail joint. Preferably this inclination is about 15° from the horizontal. At the same time it is preferable that the plane of the division through the shank, neck and head should be substantially horizontal, for reasons hereinbefore referred to, when the bolt is so positioned. I attain this desired arrangement by twisting the bolt approximately midway of its length until the median plane of the slot lies at a suitable angle, say 15° , to the division 3 between the parts of the unslotted shank of the bolt (see Figs. 1 and 4). The twist is preferably confined to a small part of the length of the bolt in order to ensure that the part of the shank of the bolt which may come into contact with the end of the slot in the web of the rail will engage equally with both parts.

From the above description it will be seen that we have devised a construction of bolt which will satisfactorily attain the objects of our invention as set out in the statement to this specification.

What we claim as our invention is:

A slotted bolt comprising a slotted portion; and a longitudinally divided non-slotted stem in which the plane of division lies at an acute angle to the median plane of the slot, and includes a divided twisted portion forming a connection between the two parts aforesaid and in which the plane of division turns through the acute angle aforesaid.

Signed at Toronto, Canada, this 22nd day of December 1927.

JOHN P. NORTHEY.
